United States Patent Office

Des. 211,863
Patented Aug. 6, 1968

211,863

GARAGE DOOR

Paul E. Pemberton, Irving, and Sheldon D. Loose and
Anthony E. Greene, Dallas, Tex., assignors to Over-
head Door Corporation, Dallas, Tex., a corporation of
Indiana

Filed June 26, 1967, Ser. No. 7,596

Term of patent 14 years

(Cl. D13—1)

FIG. 1

FIGURE 1 is a front elevational view of a garage door embodying our new design;

FIGURE 2 is a sectional view thereof taken along the line II—II in FIGURE 1;

FIGURE 3 is an enlarged fragment of the lower right corner of FIGURE 1; and

FIGURE 4 is the reverse side of said fragment.

We claim:

The ornamental design for a garage door, as shown.
